J. E. BOLAND.
RAIL JOINT.
APPLICATION FILED OCT. 15, 1913.

1,108,324.

Patented Aug. 25, 1914

UNITED STATES PATENT OFFICE.

JOHN E. BOLAND, OF ARNOLD, PENNSYLVANIA, ASSIGNOR OF ONE-HALF TO JOHN ERB,
OF ARNOLD, PENNSYLVANIA.

RAIL-JOINT.

1,108,324.

Specification of Letters Patent. Patented Aug. 25, 1914.

Application filed October 15, 1913. Serial No. 795,335.

To all whom it may concern:

Be it known that I, JOHN E. BOLAND, a citizen of the United States, residing at Arnold, in the county of Westmoreland and 5 State of Pennsylvania, have invented certain new and useful Improvements in Rail-Joints, of which the following is a specification, reference being had to the accompanying drawings.

10 This invention relates to new and useful improvements in rail joints and more particularly to a device wherein the use of nuts, bolts and the like is eliminated, the object of 15 the invention being to provide a rail joint whereby the meeting ends of two rails may be readily connected together and which will securely hold the rail ends against lateral movement.

Another object of the invention is the provision of a rail joint of the above character 20 which will possess advantages in points of efficiency and durability, is inexpensive of manufacture and at the same time is simple in construction and operation.

25 With the above and other objects in view, the invention consists in the novel features of construction and the combination and arrangement of parts to be hereinafter more fully described, pointed out in the claim and 30 shown in the accompanying drawings, in which—

Figure 1 is a detail perspective view illustrating the application of my invention; Fig. 2 is a transverse sectional view of a rail illustrating my invention in elevation; Fig. 3 is a top plan view of the joint chair; Fig. 4 is a similar view illustrating the chair in its operative position; Fig. 5 is a horizontal sectional view; Fig. 6 is a detail side elevation of one end of the rail; and Fig. 7 is a similar view of the opposite end of the rail.

Referring more particularly to the drawings, 1 indicates the cross tie which is provided on its upper face and at each end 45 thereof with a recess 2 in which the base portion of my improved joint chair 3 is disposed. From the accompanying drawings it will be readily apparent that I prefer to form the joint chair 3 in one solid piece, 50 which comprises a base portion 4, inwardly extending inclined members 5 which are adapted to engage over the inclined base flanges of the rails and the upwardly projecting parallel side members 6 having perpendicular inner faces, as shown at 7 to en-

gage the web portions of the rails, the upper edges of the side walls 6 being adapted to engage beneath the tread of the rail, as clearly shown in Fig. 2. The side walls 6 are connected at their upper edges by means of a web 8, said web being arranged nearer one end of the side walls than the other so as to provide a long recess 9 and a short recess 10 between the upper ends of the side walls. It will be noted that by having the 60 long and short recesses 9 and 10, a broken rail may be quickly and readily removed from the track without disturbing the adjacent rails. This operation is carried out by moving the joint chair 3 longitudinally 65 upon the end of the rail, the web portion of which is disposed within the recess 9. It will be understood that in forming the recesses 9 and 10, the recess 9 will be of sufficient length so that when the joint chair is 70 in its operative position, the space between the web of the rail in notch 12 and the inner end of the recess being equal to the entire length of the recess 10 so that the joint chair 75 3 may be slid upon the rail and the opposite rail be entirely removed from the shorter recess. In this manner, a broken rail may be quickly and readily removed from any part of the track without disturbing the adjacent rails. One end of each of the rails is provided in its web portion with the recess 11 and the other end thereof being provided 80 with the recess 12 which is somewhat longer than the recess 11 so that the two ends of the rail may readily fit within the recesses 9 and 10, the longer recess 12 coinciding with the recess 9 and the shorter recess 11 coinciding with the recess 10, the inner ends of the treads of the rails meeting above the web portion 8. From this it will be seen 85 that when the rail ends are arranged in their operative position between the side walls 6, all lateral movement of the rail ends will be prevented. The ends of the rails are securely retained in position by means of the 90 spikes 13 which are driven down through the inclined members 5, through the notches 14 formed in the ends of the rail and into the wooden tie 1. Thus it will be seen that the joint chair 3 will be securely held against 95 any movement whatever through the medium of the spikes 13 and the recess 2.

It will be readily apparent from the above description taken in connection with the accompanying drawings that I have pro- 100 105 110

vided a simple and durable rail joint whereby the meeting ends of two rails may be readily and effectively connected together without the use of bolts, nuts or similar 5 fastening means and at the same time will be securely held in their operative positions. It will also be apparent that my joint chair is extremely simple in construction and can be manufactured at a comparatively low 10 cost.

While I have shown and described the preferred form of my invention, it will be obvious that various changes in the details of construction and in the proportions may 15 be resorted to for successfully carrying my invention into practice without sacrificing any of the novel features or departing from the scope of the appended claim.

What I claim is:—

20 The combination with the meeting ends of two rails, the web portion of one of said rails being provided with a short recess and

the web portion of the other of said rails being provided with a long recess, a joint chair including a base, inclined portions 25 formed on said base, side walls extending upwardly from the inclined portions, a web connecting the upper ends of said side walls and having its upper face flush with the upper edges of the side walls to provide an 30 unbroken surface upon the upper face of the connection, said web forming long and short recesses adapted to coincide with the long and short recesses of the rail ends, whereby one of said rail ends may be moved 35 longitudinally within the joint chair to disengage the same therefrom.

In testimony whereof I hereunto affix my signature in the presence of two witnesses.

JOHN E. BOLAND.

Witnesses:

JOSEPH J. STEINER,
R. CHIODO.
